United States Patent Office

Des. 206,634
Patented Jan. 3, 1967

206,634

SIREN

Leo A. Guthart, Old Westbury, N.Y., assignor to Alarm Device Manufacturing Company, a division of Pittsburgh Railways Company, Inc., a corporation of Pennsylvania

Filed June 23, 1966, Ser. No. 2,786

Term of patent 14 years

(Cl. D72—1)

FIG. 1

FIG. 2

FIG. 1 is a perspective view taken from the front and one side of a siren embodying my new design; and

FIG. 2 is a perspective view taken from the rear and side shown in FIG. 1, the undisclosed side being a mirror image of the side shown.

I claim:

The ornamental design for a siren, as shown and described.
